[57] ABSTRACT

Compounds of the following formula possess central nervous system depressant properties in warm blooded animals:

in which

R, R¹ and R² are independently selected from the group consisting of —H and lower alkyl radicals; X is a member selected from the group consisting of —CH₂OH, —CHO, —CO₂R⁵, in which R⁵ is —H or lower alkyl,

Y is a member selected from the group consisting of

and —(CH₂)_n—Z, in which

R³ and R⁴ are independently —H, lower alkyl or perfluoro-lower alkyl radicals, with the proviso that when R and R² are —H, R³ is lower alkyl, Z is —H or —OH, and n is one of the integers 3 or 4;

and

pharmaceutically acceptable acid addition salts thereof.

8 Claims, No Drawings

2-ARYL-4-SUBSTITUTED-AMINO-5-PYRIMIDYL DERIVATIVES

BACKGROUND OF THE INVENTION

4-Anilinopyrimidine-5-carboxylic acids and esters have been described by Juby et al., J. Med. Chem., vol. 10, pp. 954-957 (1967) as possessing anti-inflammatory, analgetic and anti-pyretic activities. The compounds of Juby et al. were considered to possess significant activity when they produced more than 30 per cent inhibition of carrageenin induced edema in the rat foot method. Compounds of the oxazolo[2,3-b] pyrimido[4,5-d][1,3]oxazinone series, prepared by the ring closure of a 5-carboxy-4-hydroxyethylamino-2-phenyl-pyrimidine in the presence of an acid anhydride are disclosed in U.S. Pat. No. 3,563,984 granted Feb. 16, 1971 to Kim et al.

BRIEF DESCRIPTION OF THE INVENTION

In accordance with this invention, there is provided a group of chemical compounds which produce central nervous system depressant effects when administered to warm blooded animals, processes for their production, methods for their administration and administrable compositions.

The compounds of this invention may be depicted by the structural formula:

in which R, R¹ and R² are independently selected from the group consisting of -H and lower alkyl radicals; X is a member selected from the group consisting of -CH₂OH, -CHO,

-CO₂R⁵, in which

R⁵ is -H or lower alkyl,

Y is a member selected from the group consisting of

and

-(CH₂)n-Z, in which

R³ and R⁴ are independently -H, lower alkyl or per-fluoro-lower alkyl radicals, with the proviso that when R and R² are -H, R³ is lower alkyl,

Z is -H or -OH, and

n is one of the integers 3 or 4; and pharmaceutically acceptable acid addition salts thereof.

The expression "lower alkyl" used throughout the specification, is used to include straight and branched chain univalent hydrocarbon radicals containing from 1 to 7 carbon atoms, such as methyl, ethyl, i-propyl, n-propyl, n-butyl, n-hexyl, and the like. The expression "pharmaceutically acceptable acid addition salts" is used to include those non-toxic acid addition salts which may be formed with both organic and inorganic acids such as hydrochloric, hydrobromic, sulfuric, phosphoric, methane sulfonic, nitric, p-toluene sulfonic, acetic, citric, maleic, succinic, and the like.

The compounds of this invention are prepared by reacting an arylamidine hydrochloride with a dialkyl 2-alkoxymethylene alkanedioate -

followed by displacement of the 4-hydroxyl group with chlorine by reaction of PCl_3 , PCl_5 , SOCl_2 , POCl_3 , and the like, and dechloroamination with either an aromatic amine of the formula -

an aliphatic amine of the formula -

$\text{H}_2\text{N}(\text{CH}_2)_n\text{Z}$, where the groups R, R¹, R², R³, R⁴ and Z and the value of n are hereinabove defined. Thus, the amine reactants are desirably aniline, m-trifluoromethylaniline, 2,3-dimethylaniline, methylamine, ethylamine, propylamine, 3-hydroxypropylamine, butylamine, N-ethylaniline, N-methyl-3-trifluoromethylaniline, N-ethyl-3-trifluoroaniline, and the like.

An especially useful aliphatic amine is 3-hydroxypropylamine, which may be cyclized through the ortho carboxyl group in the presence of an acylating agent such as acetic anhydride to form the lactone 1,3-oxazino-[2,3-b]pyrimido[4,5-d][1,3]oxazin-5-one.

The 5-carboalkoxy substituent of the pyrimidine nucleus may be reduced selectively by a reagent such as LiAlH_4 or $(\text{t-butoxy})_3\text{LiAlH}$ to afford the 5-hydroxymethyl compound, which undergoes mild oxidation with a reagent such as MnO_2 to yield the 5-aldehydo compound.

The compounds of this invention are physiologically active central nervous system depressants. The compounds were evaluated in accordance with the following test procedures, the biological activity of the specifically exemplified compounds being presented in conjunction with the specific preparative procedure, infra:

PROCEDURE I

The compounds were administered orally and intraperitoneally to three mice (14 to 24 grams) at doses ranging from 0.04 to 400 milligrams per kilogram of host body weight. The animals were watched for a minimum of two hours during which time signs of general stimulation (i.e., increased spontaneous motor activity, hyperactivity on tactile stimulation, twitching), general depression (i.e., decreased spontaneous motor activity, decreased respiration) and autonomic activity (i.e., miosis, mydriasis, diarrhea) were noted.

The compounds tested were found to be physiologically active compounds in experimental and comparative pharmacology and are of value in the treatment of mammals, e.g., mice, rats, etc., who are responsive to treatment with central nervous system depressant

agents. Specifically the compounds may be administered for the purpose of inducing a calming effect in mammals.

The compounds of this invention are individually unique in their activity as anti-inflammatory agents. The pertinent testing procedures by which anti-inflammatory activity was evaluated are as follows:

PROCEDURE II

From 1.0 to 100 milligrams of the compound tested per kilogram body weight was administered orally to six rats (120-160 grams in weight, averaged between groups) with a six rat control being administered aqueous vehicle with no active compound. 60 minutes after drug administration, edema was induced by injection of 0.05 milliliters of 1 per cent carrageenin solution into the subplantar tissue of the rat's right hind paw. The paw volume was immediately volumetrically determined with a plethysmograph and again 3 hours later. The mean volume swelling for the control group was determined and compared to the test group. Swelling inhibition of 23 per cent or more was considered to be indicative of an active compound.

PROCEDURE III

This procedure is a modification of the procedure disclosed in Mizushima, Arch. In. Pharmacodyn., vol. 149, pp. 1-7 (1964).

Test solutions are prepared to contain 2.5 milliliters of buffered 1 per cent albumin (bovine serum Fraction V) and 2.5 milliliters of buffer or the solution being tested. The buffer solvent consists of 0.05 molar tris(hydroxymethyl)amino methane, (pH6.5). Up to 2.5 per cent final solution concentration dimethylformamide may be employed to solubilize the compound being tested. The control and test systems are heated at 69°C for 4 minutes, cooled and their turbidities are read at 54 millimicrons. Test compounds that decrease the solution turbidity more than 20 per cent at a concentration up to 1 milligram per liter are deemed active.

PROCEDURE IV

This procedure is a modification of the procedure of Gerber et al., Biochem. Pharmacol., vol. 16, pp. 115-123 (1967).

A mixture of 3 milliliters of 2.07 millimolar solution of the test compound, 3 milliliters of 4.1 per cent human serum albumin (Fraction V), and 0.2 milliliters of 2 millimolar 5,5'-dithiobis(2-nitrobenzoic acid) in 0.1 molar aqueous potassium phosphate buffer solution (pH 7.4) is incubated at 30°C. The reaction rates are measured for 40 minutes by reading absorbance at 412 millimicrons. The net per cent increase produced by the test compound is calculated for 10 and 30 minute periods. A minimum 20 per cent acceleration denotes activity of the test compound at a maximum concentration of 1 milligram per liter. In theory, the anti-inflammatory agent accelerates the disulfidesulphydryl interchange in serum albumen as is evidenced by an increase in the formation of pigmented 5-thio-2-nitro benzoic acid from serum albumin and 5,5'-dithiobis(2-nitrobenzoic acid).

PROCEDURE V

This test is a modification of the procedure of Skidmore et al., J. Pharm. Pharmacol., vol. 17, pp. 671-673 (1965).

A reaction mixture is prepared to contain 2.0 milliliters of 2.01 per cent bovine serum albumin (Fraction V), 2.0 milliliters of 0.15 millimolar 2,4,6-trinitrobenzaldehyde, and 2.0 milliliters of a 3.0 millimolar (or less) solution of the test compound, all in 0.1 molar sodium phosphate (pH 7.5). Dimethylformamide may be present up to 3 per cent of the final volume to facilitate solubilization. The rate of reaction is measured at room temperature by reading the absorbance at 425 and 525 millimicrons over a 40 minute period. The net per cent inhibition of color formation is calculated at 30 minutes for both wave lengths and averaged. A compound that decreases the color formation by more than 20 per cent at 1 milligram per liter is considered to be active.

When the compounds of the invention are employed as described above they may be administered alone or in combination with pharmacologically acceptable carriers, the proportion of which is determined by the chosen route of administration and standard pharmaceutical practice. For example, they may be administered orally in tablet or capsule form with conventional flavors, diluents, lubricants, disintegrators or binding agents as may be required. They may be administered orally in the form of a solution or they may be injected parenterally. For parenteral administration they may be used in the form of a sterile solution containing other solutes, for example, enough saline or glucose to make the solution isotonic. It is most advantageous to provide the compound as a dry powder in a suitable container so that it may be admixed with a suitable aqueous vehicle prior to administration.

Tablets containing the central nervous system depressants of this invention may be formulated by admixing a unit dosage amount of the active compound with microcrystalline cellulose N.F.; magnesium stearate U.S.P.; and a filler such as lactose U.S.P. to obtain any desired ultimate tablet weight. Furthermore, to prepare injectable formulations, the acid addition salt of the desired compound of compound mixture of this invention is combined with lactose U.S.P. to form a packageable (sealed glass ampoule, or the like) mix which, when combined with the injection vehicle, such as sterile water containing about 1 per cent benzyl alcohol and 0.6 per cent sodium acetate/acetic acid buffer, may be parenterally employed. The specific formulation, for tablets, capsules or injectables depends upon the host and formulation techniques employed.

DETAILED DESCRIPTION OF THE INVENTION

The following Preparations 1-3 illustrate the technique employed to prepare the intermediates from which the biologically active compounds of this invention, presented in Examples 1 - 11, were prepared.

PREPARATION I

Ethyl 4-chloro-6-methyl-2-phenyl-5-pyrimidinecarboxylate.

With vigorous stirring, add 7.8 grams of benzamidine hydrochloride to a freshly prepared solution of sodium ethoxide (2.3 grams sodium in 100 milliliters absolute ethanol). Add 11.5 grams diethyl ethoxyethylenemethyl-

ionate to the mixture and reflux for 1½ hour. Chill the reaction mixture and filter to remove inorganic salts. Evaporate the filtrate to dryness under reduced pressure. Dissolve the residue in water and acidify the solution with hydrochloric acid. Collect the precipitate and recrystallize from ethyl acetate to obtain 3.6 grams of the title compound which exhibits an uncorrected melting point of 174°-176°C.

Elemental Analysis: C₁₄H₁₄N₂O₃
Calculated: C, 65.10; H, 5.46; N, 10.85.
Found: C, 65.25; H, 5.45; N, 10.88.

Reflux a mixture of the product of the preceding paragraph (5.7 grams) and phosphorus oxychloride (60 milliliters) for 3.5 hours. Remove the unreacted phosphorus oxychloride under reduced pressure. Treat the residual oil with crushed ice to obtain 5.2 grams of 20 ethyl 4-chloro-6-methyl-2-phenyl-5-pyrimidinocarboxylate as a yellow solid.

PREPARATION II

Ethyl 4-chloro-2-phenyl-5-pyrimidinocarboxylate

By following the instruction of Procedure I, with the exception that diethyl ethoxymethylenemalonate is used as the reactant in lieu of diethyl ethoxyethylenemalonate, yields 5-carbethoxy-4-hydroxy-2-phenylpyrimidine which may be dehydroxychlorinated to the 4-chloro derivative (Kim & Santilli, J. Heterocycl. Chem., vol. 6. pp. 819-828 (1969).

PREPARATION III

N-lower alkyl- α,α,α -trifluoro-m-toluidine.

Acetylate α,α,α -trifluoromethyl-m-toluidine (32 grams) by adding thereto in dropwise manner 22 grams of acetic anhydride while stirring the mixture. After the exothermic reaction subsides, heat the mixture on a steam bath for 20 minutes. Cool the mixture. Filter the product and wash it with water. Recrystallize the product from diethylether-petroleum ether to yield 29 grams of N-acetyl- α,α,α -trifluoro-m-toluidine melting at 101°-103°C.

Elemental Analysis: C₈H₁₄F₃NO
Calculated: C, 53.20; H, 3.97; N, 6.89
Found: C, 52.96; H, 4.06; N, 6.85

Reduce 30.5 grams of the product of the preceding paragraph with 5.7 grams of lithium aluminum hydride in tetrahydrofuran to give 17 grams of N-ethyl- α,α,α -trifluoro-m-toluidine which has a boiling point of 40°C. at 0.75 millimeters mercury pressure.

Elemental Analysis: C₉H₁₆F₃N
Calculated: C, 57.74; H, 5.38; N, 7.48
Found: C, 57.09; H, 5.26; N, 7.51

Following the above detailed procedure, various N-lower alkyl- α,α,α -trifluoro-m-toluidine derivatives such as the N-propyl and N-butyl compounds may be prepared.

The following examples present specific instructions in accordance with which the compound aspects of this invention were prepared.

EXAMPLE I

Ethyl 4-methyl-2-phenyl-6-(α,α,α -trifluoro-m-toluidino)-5-pyrimidinocarboxylate.

Reflux a mixture of ethyl 4-chloro-6-methyl-2-phenyl-5-pyrimidinocarboxylate (2.6 grams), α,α,α -trifluoro-m-toluidine (10 milliliters) and ethanol (15 milliliters) for 2 hours. Cool the reaction mixture, filter the precipitate and wash the product with water. Crystallize the product from ethanol to obtain 2.5 grams of the title compound which has a melting point of 15 120°-123°C.

Elemental Analysis: C₂₁H₁₈F₃N₂O₂
Calculated: C, 62.84; H, 4.52; N, 10.47
Found: C, 62.93; H, 4.53; N, 10.52

EXAMPLE II

25 4-Methyl-2-phenyl-6-(α,α,α -trifluoro-m-toluidino)-5-pyrimidinocarboxylic acid

Reflux the ethyl ester prepared in Example I (2.1 grams) for 3 hours with 25 milliliters of 15 per cent aqueous NaOH and 5 milliliters of ethanol. Precipitate 30 the sodium salt of the title product by cooling the reaction mixture. Filter the precipitate, dissolve it in hot water and filter the solution. Acidify the filtrate with dilute HCl to obtain 1.8 grams of the title compound which melts at 118°-120°C. with decomposition.

Elemental Analysis: C₁₉H₁₄F₃N₂O₂
Calculated: C, 61.13; H, 3.78; N, 11.29
Found: C, 61.00; H, 3.88; N, 11.41

40 This carboxylic acid is a central nervous system depressant, demonstrating activity at a dosage level of 127 milligrams per kilogram body weight and above. The activity noted in mice, upon oral administration in 45 accordance with Test Procedure No. 1, supra, decreased motor activity, sedation, decreased respiration and hyperemia. In addition, anti-inflammatory activity was observed in vivo and in vitro in accordance with the Test Procedures No. II, III at 0.09 millimolar concentration and V at 0.3 millimolar concentration supra.

EXAMPLE III

2-Phenyl-4-(2,3-xylidino)-5-pyrimidinocarboxylic acid and the ethyl ester thereof

55 Following the technique of Example I react 2,3-xylidine and ethyl 4-chloro-2-phenyl-5-pyrimidinocarboxylate to yield the ethyl ester which is hydrolyzed to afford the free acid.

EXAMPLE IV

Ethyl 4-(N-ethyl- α,α,α -Trifluoro-m-toluidino)-2-phenyl-5-pyrimidinocarboxylate

Reflux a mixture of 5-carbethoxy-4-chloro-2-phenylpyrimidine (6.5 grams), N-ethyl- α,α,α -trifluoro-m-toluidine (5 grams), sodium carbonate (2.7 grams) and N,N-dimethyl formamide (45 milliliters) for 3.5 hours. Pour the reaction mixture into cold water to sep-

arate the product as an oil. Wash the oil several times with water and cool to cause solidification. Filter and wash with diethyl ether to obtain 4.0 grams of product which upon recrystallization from petroleum ether affords the title compound melting at 100°-102°C.

Elemental Analysis: $C_{22}H_{20}F_3N_3O_2$
 Calculated: C, 63.61; H, 4.85; N, 10.12
 Found: C, 63.27; H, 5.14; N, 10.22

The ester prepared in accordance with the preceding Example exhibited anti-inflammatory activity at a minimum concentration of 0.8 millimoles per liter in accordance with Test Procedure No. III.

EXAMPLE V

4-(ethyl- α,α,α -trifluoro-metoluidine)-2-phenyl-5-pyrimidinocarboxylic acid

Heat a mixture of the ethyl ester of Example IV (1.5 grams), 50 per cent aqueous dimethylsulfoxide (75 milliliters), 15 per cent aqueous sodium hydroxide solution (4.5 milliliters) and 30 milliliters of dimethylsulfoxide on a steam bath for 6 hours. Allow the temperature of the mixture to fall to room temperature and acidify with 3N HCl to precipitate the free acid. Filter and wash with water to yield 1.4 grams of the title compound. An analytically pure compound melting at 180°-182°C. is obtained by recrystallization from aqueous ethanol.

Elemental Analysis: $C_{20}H_{16}F_3N_3O_2$
 Calculated: C, 62.01; H, 4.16; N, 10.80
 Found: C, 61.59; H, 4.07; N, 10.85

The free acid prepared by the method presented in the preceding paragraph produced a central nervous system depressant effect when administered orally and intraperitoneally at doses as low as 127 milligrams per kilogram host body weight, to mice, as evidenced by decreased motor activity, decreased respiration mydriasis and hyperemia. Furthermore, the free acid produced an anti-inflammatory effect when tested in accordance with Procedures III at 0.03 millimolar minimal effect and V at 0.08 millimolar concentration.

EXAMPLE VI

Ethyl 4-(3-hydroxypropylamino)-2-phenyl-5-pyrimidinocarboxylate

Add 15 grams of 4-chloro-5-carbethoxy-2-phenyl pyrimidine portionwise to 30 milliliters of 3-aminopropanol in 30 milliliters of ethanol, with stirring. Heat gently to initiate the reaction and continue stirring at room temperature for 15 minutes at which time the temperature of the solution is raised with a steam bath for 10 minutes. Quench in water to separate the oily product which solidifies on cooling and scratching. Filter to obtain 20 grams of product which melts at 63°-66°C. after recrystallization from diethyl ether.

Elemental Analysis: $C_{16}H_{19}N_3O_3$
 Calculated: C, 63.77; H, 6.36; N, 13.95
 Found: C, 63.65; H, 6.49; N, 13.99

The product of the preceding example produces central nervous system depressant effects on mice when administered orally at a concentration as low as 127 milligrams per kilogram host body weight as evidenced by hyperactivity to touch decreased motor activity, sedation and decreased respiration.

EXAMPLE VII

10 4-(3-Hydroxypropylamino)-2-phenyl-5-pyrimidinocarboxylic acid

Reflux a mixture of the ethyl ester of Example VI (15 grams), 15 per cent aqueous NaOH solution (45 milliliters), and ethanol (10 milliliters) for 0.5 hour. Adjust the pH of the solution to about 2 by adding HCl, thereby precipitating the free acid. Filter and wash with water to obtain 8.0 grams of product having a melting point of 223°-225°C. Further purification of the title compound by dissolving in base followed by acidification yields a product melting at 228°-230°C.

Elemental Analysis: $C_{14}H_{15}N_3O_3$
 Calculated: C, 61.53; H, 5.53; N, 15.38
 Found: C, 61.33; H, 5.66; N, 15.61

4-(3-Hydroxypropylamino)-2-phenyl-5-pyrimidinocarboxylic acid produced central nervous system depressant effects in mice when oral doses as low as 127 milligrams per kilogram body weight are administered. The observed effects are decreased motor activity, sedation, decreased respiration, augmented flexor, reflex, mydriasis and hyperemia. In addition, the free acid produces an anti-inflammatory effect upon oral administration to rats in accordance with Test Procedure II.

EXAMPLE VIII

40 9,10-Dihydro-6a-methyl-2-phenyl-5H,6aH,8H-[1,3]oxazino[2,3b]-pyrimido[4,5-d][1,3]oxazin-5-one
 Reflux a mixture of 4-(3-hydroxypropylamino)-2-phenyl-5-pyrimidinocarboxylic acid (3 grams) with acetic anhydride (40 milliliters) for about 30 minutes to obtain a clear solution. Remove the acetic anhydride in vacuo to leave a resinous material which crystallized from ethyl acetate after several washings with anhydrous diethyl ether to afford the title compound melting at 153°-155°C.

Elemental Analysis: $C_{16}H_{15}N_3O_3$
 Calculated: C, 64.63; H, 5.09; N, 14.14
 Found: C, 64.66; H, 5.06; N, 13.95

The lactone 1,3-oxazino[2,3-b]pyrimido[4,5-d][1,3]-oxazin-5-one produces central nervous system depressant activity when administered intraperitoneally to mice in doses as low as 40 milligrams per kilogram body weight, as evidenced by decreased motor activity and decreased respiration.

EXAMPLE IX

65 2-Phenyl-4-(α,α,α -trifluoro-m-toluidino)-5-pyrimidinemethanol.

Reduce 15.3 grams of ethyl 2-phenyl-4-(α,α,α -trifluoro-m-toluidino)-5-pyrimidinocarboxylate with

1.6 grams of LiAlH_4 using tetrahydrofuran as the reaction solvent. After 5 hours reaction time, the crude product weighed 13.8 grams. Crystallization from ethanol yielded an analytically pure sample melting at $174^\circ\text{--}177^\circ\text{C}$.

Elemental Analysis: $\text{C}_{18}\text{H}_{14}\text{F}_3\text{N}_3\text{O}$
Calculated: C, 62.61; H, 4.09; N, 12.17
Found: C, 62.61; H, 4.12; N, 12.10

The product of the preceding example produces central nervous system depressant effects in mice when administered intraperitoneally in doses as low as 40 milligrams per kilogram host body weight, evidenced by decreased motor activity, decreased respiration and ataxia at a dose as low as 400 milligrams per kilogram body weight.

EXAMPLE X

2-Phenyl-4-(2,3-xylidino)-5-pyrimidinemethanol
Following the procedure of Example IX, reduce 13.5 grams of ethyl 2-phenyl-4-(2,3-xylidino)-5-pyrimidinecarboxylate with 2.0 grams of LiAlH_4 in 250 milliliters of tetrahydrofuran to obtain 11 grams of the title compound which melts at $170^\circ\text{--}174^\circ\text{C}$. Recrystallization from ethanol yields the compound melting at $172^\circ\text{--}174.5^\circ\text{C}$.

Elemental Analysis: $\text{C}_{19}\text{H}_{19}\text{N}_3\text{O}$
Calculated: C, 74.73; H, 6.27; N, 13.76
Found: C, 74.49; H, 6.28; N, 13.70

The product of Example X produces central nervous system depressant effects in mice when administered orally in doses as low as 400 milligrams per kilogram and intraperitoneally in doses as low as 127 milligrams per kilogram host body weight. Thus, the depressant effects are observed in hyperactivity to touch, decreased motor activity, ataxia, decreased respiration and ptosis.

EXAMPLE XI

2-Phenyl-4-(α,α,α -trifluoro-m-toluidino)-5-pyrimidinecarboxaldehyde

Reflux 3.4 grams of 2-phenyl-4-(α,α,α -trifluoro-m-toluidino)-5-pyrimidinemethanol, 3.4 grams of active manganese dioxide and 140 milliliters at benzene for 7 hours, continuously removing water as it is produced. Cool to room temperature. Remove the manganese dioxide by filtration. Remove the benzene under reduced pressure to leave 3.0 grams of solid residue melting at $143^\circ\text{--}145^\circ\text{C}$. Recrystallization of the product from acetone yielded the title compound melting at $145^\circ\text{--}147^\circ\text{C}$.

Elemental Analysis: $\text{C}_{18}\text{H}_{12}\text{F}_3\text{N}_3\text{O}$
Calculated: C, 62.67; H, 3.53; N, 12.24
Found: C, 62.63; H, 3.42; N, 11.97

5

The product of Example X produces central nervous system depressant effects in mice at oral doses as low as 12.7 milligrams per kilogram host body weight, evidenced by decreased motor activity sedation and decreased respiration.

What is claimed is:

1. A compound of the formula:

in which R^5 is -H or lower alkyl.

2. The compound of claim 1 which is 4-methyl-2-phenyl-6-(α,α,α -trifluoro-m-toluidino)-5-pyrimidinecarboxylic acid.

25

3. A compound of the formula

in which R^5 is -H or lower alkyl.

35

4. The compound of claim 3 which is 4-(N-ethyl- α,α,α -trifluoro-m-toluidino)-2-phenyl-5-pyrimidinecarboxylic acid.

5. A compound of the formula:

in which

X is $-\text{CH}_2\text{OH}$ or $-\text{CHO}$; R^3 is -H or alkyl of 1 to 7 carbon atoms; and R^4 is -H, alkyl of 1 to 7 carbon atoms or perfluoroalkyl of 1 to 7 carbon atoms.

50

6. The compound of claim 5 which is 2-phenyl-4-(α,α,α -trifluoro-m-toluidino)-5-pyrimidinemethanol.

7. The compound of claim 5 which is 2-phenyl-4-(2,3-xylidino)-5-pyrimidinemethanol.

55

8. The compound of claim 5 which is 2-phenyl-4-(α,α,α -trifluoro-m-toluidino)-5-pyrimidinecarboxaldehyde.
